UNITED STATES PATENT OFFICE.

FRANK J. ARNOLD, OF BROOKLYN, NEW YORK, ASSIGNOR TO THE WHITEHEAD & HOAG COMPANY, OF NEWARK, NEW JERSEY, A CORPORATION OF NEW JERSEY.

DESIGN FOR A LEAGUE BUTTON.

Application filed November 24, 1925. Serial No. 15,531. Term of patent 14 years.

To all whom it may concern:

Be it known that I, FRANK J. ARNOLD, a citizen of the United States, residing at Brooklyn, county of Kings, New York, have invented a new, original, and ornamental Design for a League Button, of which the following is a specification, reference being had to the accompanying drawing, forming part thereof.

I claim:

The ornamental design for a league button as shown.

FRANK J. ARNOLD.
